UNITED STATES PATENT OFFICE.

FREDERIC BORMANN, OF IPSWICH, SOUTH DAKOTA.

BURNER.

Application filed February 6, 1923. Serial No. 617,212.

To all whom it may concern:

Be it known that I, FREDERIC BORMANN, a citizen of the United States, residing in Ipswich, in the county of Edmunds and 5 State of South Dakota, have invented a new and useful Burner, of which the following is a specification.

My invention relates to improvements in burners adapted particularly, though not 10 exclusively for use in stoves and furnaces.

One object is to supply a simple, durable and inexpensive liquid fuel burner adapted to be readily applied to the different types of stoves and furnaces.

15 Another object is to provide a novel device of the present nature, wherein a uniformly high degree of efficiency is attained under the different conditions met in the various types of stoves and furnaces.

20 With the foregoing and other objects in view, which will appear in the following description, the invention resides in the novel combination and arrangement of parts and in the details of construction hereinafter 25 described and claimed.

Fig. 1 is a side elevation of a burner embodying my invention, the same being shown in connection with a stove, which is illustrated in section and Fig. 2 is a perspective view of the burner unit.

Referring to the drawings, it will be observed that my improvement includes a base A, a coil B supported on the base and a spreader plate C within the coil. The 35 burner may be placed in any of the usual types of stoves or furnaces with the legs 10 of the base resting upon the stove or furnace grate 11. Said base is designed to form a generating fluid receptacle 12 in which is placed asbestos wool 12^a or other non-combustible absorbent material. The coil B consists of a pipe bent in a number of loops b as shown in Fig. 2. Said coil rests on its side in the fluid receptacle 12, the ends b' 40 thereof being joined through feed pipe branches 13 with a feed conduit 14 leading to a source of liquid fuel supply. The ends b' of the coil B are preferably connected with the fuel conduit 14 outside the walls of a stove or furnace so that no joints or 45 connections will be subjected to the heat therein. A feed valve 15 and check valve 16 of suitable conventional types are incorporated in the supply conduit 14. A gas 50 outlet opening 17 formed in the lower turn

of the intermediate loop b of the coil B issues upward as shown in Fig. 2. The spreader plate C, reaching through the coil B, is supported at various elevations therein. Said plate is attached by means of connecting arms 18 to an upright hanger bar 19. A pin 20 anchored in a depending flange 21 on the base A is selectively inserted in a plurality of apertures 19^a formed in the hanger bar 19. Hooks 19^b on the lower end of said bar 19 are formed to catch the bale 22 carrying a weight 23. The branches 22^a of the bale 22 are of considerable length to permit the hooking of the bale in any of the various hooks 19^b without 70 interference between the lower extremity of the bar 19 and the top of the weight 23. The bar 19 hangs in any convenient position between the bars of the grate 11 of a stove or furnace to which the burner is applied. The adjustment provided by the hooks 19^b permits of the location of the weight 23 at various elevations to suit ash pits of various depths. The vertical adjustment of the spreader plate C, accomplished by the insertion of the pin 20 in different apertures 19^a in the hanger bar 19, provides for suitably spreading the flame issuing upward from the gas outlet 17, and thereby produces the desired generating effect in the coil under the various conditions met in the different installations of the burner. The coil B being fed from both ends thereof results in uniform generation and output of the gas. 85

In use, the asbestos material 12^a is first saturated with a generating fluid which is ignited. The heat absorbed by the coil B causes the initial generation of gas from the liquid fuel contained within the loops b thereof. This is followed by the ignition of gas issuing from the gas opening 17. The burning of the gas creates heat, which is spread outwardly against the turns of the coil B through its length, said heat serving 95 to continue generation within said coil.

Changes in the specific form of my invention, as herein disclosed, may be made within the scope of what is claimed without departing from the spirit of my invention. 105

Having described my invention, what I claim as new and desire to protect by Letters Patent is:

1. In a burner for liquid fuel adapted to be placed in the heating chamber of a stove 110

- or furnace, a base formed with a generating fluid receptacle and designed to be supported upon the stove grate, a pipe having a plurality of turns therein forming a generating coil, said coil resting horizontally in said receptacle, fuel conduits communicating with said coil at both ends thereof, an intermediate loop of said coil being formed at the bottom thereof with an upwardly issuing gas outlet, a horizontal spreader plate reaching through the coil, an upright hanger-bar connected at its upper end with and carrying said plate, said bar having a plurality of intermediate apertures therein, a supported pin on the frame for selective insertion in said apertures and a weight having a vertically adjustable connection with said hanger-bar at its lower end.
2. In a burner for liquid fuel adapted to be placed in the heating chamber of a stove or furnace, a base formed with a generating fluid receptacle and designed to be supported upon the stove grate, a pipe having a plurality of turns therein forming a coil, said coil resting horizontally in said receptacle, fuel conduits communicating with said coil at both ends thereof, an intermediate loop of said coil being formed at the bottom thereof with an upwardly issuing gas outlet, a horizontal spreader plate reaching through the coil, an upright hanger-bar connected at its upper end with and carrying said plate, said bar being weighted at its lower end and having a medial, vertically adjustable mounting on said frame.
3. In a burner for liquid fuel adapted to be placed in the heating chamber of a stove or furnace, a base formed with a generating fluid receptacle and designed to be sup-
- ported upon the stove grate, a pipe having a plurality of turns therein forming a coil, said coil resting horizontally in said receptacle, fuel conduits communicating with said coil at both ends thereof, an intermediate loop of said coil being formed at the bottom thereof with an upwardly issuing gas outlet, a horizontal spreader plate reaching through the coil, an upright hanger-bar connected at its upper end with and carrying said plate, said bar having a vertically adjustable mounting on said frame.
4. In a burner for liquid fuel, a pipe having a plurality of turns therein forming a generating coil, means for supporting said coil horizontally, fuel conduits communicating with said coil at both ends thereof, an intermediate loop of said coil being formed at the bottom thereof with an upwardly issuing gas outlet, a horizontal spreader plate within the coil and adjustable means for holding said plate at various elevations.
5. In a device of the class described, a pipe bent medially in a plurality of turns to form a horizontal generating coil for application to the heating chamber of a stove, the extremities of said pipe being adapted to project outwardly through the walls of the stove for connection with a source of fuel supply, an intermediate loop of said coil being formed at the bottom thereof with an upwardly issuing gas outlet and a spreader plate disposed horizontally within said coil and adjustable vertically to assume various elevations therein.

In testimony whereof, I have signed my name to this specification.

FREDERIC BORMANN.
